CHARLES H. MCCOY, OF LOS ANGELES, CALIFORNIA, ASSIGNOR OF ONE-HALF TO
CHARLES C. BOGARDUS, OF LOS ANGELES, CALIFORNIA

HAIR-WAVING APPARATUS

Application filed December 13, 1927. Serial No. 239,632.

My invention relates to a hair waving apparatus and has for its principal object the provision of a relatively simple and easily operated apparatus that may be effectively used for imparting to the hair Marcel or water waves.

Further objects of my invention are to generally improve upon and simplify the existing forms of apparatus utilized for waving the hair,—to provide an apparatus of the character referred to having a plurality of sets of combs that engage and hold the hair in shape to produce the desired waves,—and further to provide a hair waving apparatus that will readily conform to the head, and which may be easily and quickly positioned for use upon the head and removed therefrom.

With the foregoing and other objects in view, my invention consists in certain novel features of construction and arrangement of parts that will hereinafter be more fully described and claimed and illustrated in the accompanying drawings, in which—

Fig. 1 is a perspective view of a hair waving apparatus of my improved construction in position for use upon the head.

Fig. 2 is a plan view of the apparatus positioned upon the head for use.

Fig. 3 is an enlarged section taken approximately on the line 3—3, of Fig. 2.

Fig. 4 is an enlarged view looking against the underside of one of the comb carrying bands and said view being taken looking in the direction indicated by the arrows 4—4, of Fig. 3.

Fig. 5 is an enlarged cross section taken on the line 5—5, of Fig. 3.

Fig. 6 is an enlarged cross section taken on the line 6—6, of Fig. 3.

Fig. 7 is an elevational view of the flexible portion of one of the combs utilized in my improved hair waving apparatus.

Fig. 8 is a cross section taken on the line 8—8, of Fig. 7.

Fig. 9 is a horizontal section taken on the line 9—9, of Fig. 7.

Referring by numerals to the accompanying drawings, which illustrate a practical embodiment of my invention,—10 designates

the front member of the frame of the apparatus, which front member is preferably formed of light weight metal such as aluminum, and said member being shaped so as to fit snugly across the forehead with the end portions curved downwardly so as to overlie the temples and projecting rearwardly from the lower portion of this front member is an inverted L-shaped flange 11, the depending portion of which is adapted to rest directly against the forehead and temples.

Formed in the outer upper portion of the front member 10 is a channel 12 that is adapted to be occupied by the front ends of the comb carrying straps, and the latter are clamped to the front member 10 by means of thumb screws 13 that pass through the wall of member 10 in front of channel 12.

A strap or band 14 preferably of metal, such as aluminum is shaped so as to fit upon the rear portion of the neck of the user of the apparatus and arranged to fit beneath the chin is a cup-shaped member 15, which may be of light weight metal such as aluminum or fabric, such as canvas.

Connecting the ends of the front frame member 10 with the ends of the chin cup 15 are straps 16 that occupy positions against the cheeks of the wearer, and connecting the ends of the chin cup 15 with the ends of the back neck strap 14 are straps 17 of leather or fabric that are separable and adjustable by means of ordinary buckles 18.

A centrally arranged frame member preferably a light weight metal strap or band 19 has its forward end clamped by means of one of the thumb screws 13 to the central portion of the front head band 10, and the lower rear end of this central strap is detachably connected preferably by means of a set screw or winged nut 20 to the central portion of the rear neck band 14.

Thus the frame of my improved hair waving apparatus comprises the front head band 10, the rear neck band 14, and the central band 19 that passes over the central portion of the head, and said frame being provided with the straps 17 that enable the frame to be readily positioned upon or removed from the head.

Arranged between the front band 10 and the upper portion of the center band 19 is a series of straps or bands 21, preferably formed of light weight metal, and which carry the combs that are utilized in imparting the waves to the hair.

These overhead bands or straps have the general shape of a horse shoe and they are curved lengthwise so as to conform to the curvature of the head above and to the rear of the forehead and ears. The forward ends of the bands or straps 21 are curved downwardly so as to engage in the curve 12 in the front head band 10 and the ends so positioned are detachably clamped to the front head band by the winged nuts 13, and the rear central portions of the bands are permanently secured to the central head band 19, preferably by means of rivets 22. While I have shown three of the comb carrying bands 21 it is obvious that the number of bands may be increased or decreased as desired.

Positioned beneath each strap or band 21 and spaced a short distance apart therefrom is a band or plate 23 of light weight metal, the same being permanently secured to the strap or band 21 preferably by means of rivets 24, and one edge of this strap or band 23, preferably the outer edge, is bent at right angles to the plane occupied by the body of the strap or band, and said bent portion is provided with teeth 25, which are in every way similar to the teeth of an ordinary comb.

Arranged for longitudinal sliding movement beneath each band or strap 23 is a pair of depending combs 26 that are spaced apart, and which occupy positions substantially parallel with the adjacent comb 25, and secured in the upper portions of these combs 26 are pins 27 that project upwardly through oppositely disposed arcuate slots 28 that are formed in strap 23.

The upper ends of each pair of pins 27 are pivotally connected by a short lever 29, the latter being mounted upon a pivot pin 30 that is seated in strap 23 between the arcuate slots 28.

As a result of the construction just described the combs are mounted so as to move simultaneously in opposite directions, for as each lever 29 swings on its axis the pins 27 traverse the arcuate slots 28, thereby imparting movement simultaneously to the combs 26; said combs move in opposite directions and likewise move toward or away from each other depending upon the direction of movement of said lever 29.

In order that the combs may have sufficient flexibility to traverse the sharp curved rear portions of the straps or bands 21, portions of said combs are made in sections as illustrated in Figs. 7, 8 and 9. A series of separately formed comb teeth 31 are strung on

wires 32 and the latter are connected to the main bodies of the combs and these flexible portions of the combs are arranged so that they will flex slightly as the full lengths of the combs are shifted longitudinally by movement of the levers 29.

Connecting the ends of each set of levers are small flexible wires or cables 33, and at the ends of the straps or bands 21 each pair of these wires or cables are connected to a cross bar or lever 34 that is carried by a short shaft 35, the same being journaled in the bands or straps 21 and 23 adjacent to the ends thereof, and the outer end of each shaft carrying a disk 36 having a knurled edge, and which serves as an operating handle. Thus by engaging the disks 36 and rotating the same the corresponding pair of combs will be simultaneously moved in opposite directions due to the connections between the actuated disk and combs.

In the use of my improved hair waving apparatus the frame is applied to the head as illustrated in Figs. 1 and 2, and said frame is firmly retained in position for use by proper adjustment of the straps 17. When the apparatus is positioned on the head the teeth of all of the combs project through the hair and bear on the scalp, and the various sets of combs are arranged so that they pass through the hair substantially at right angles thereto rather than in inclined planes or in planes parallel with the hair, and as a result practically all of the hair will be acted upon by the combs as the latter are manipulated.

The operator successively engages the disks 36 and partially rotates same, and as each disk is rotated the corresponding lever 34 will be swung into an angular position and through the connections 33 the levers 29 will be swung into corresponding angular positions so that one of the movable combs 26 will be moved lengthwise in one direction while the other one of the movable combs will be moved lengthwise in the opposite direction and at the same time the movable combs will approach each other as the pins 27 traverse the arcuate slots 28.

The adjacent stationary comb 25 will hold in the original position the hair engaged by the movable combs and as the latter are actuated as just described they will impart curvature or waves to the hair and an abrupt wave or fold will be formed between the two movable combs when the same have been brought into position immediately adjacent to each other.

This procedure is carried out with each pair of movable combs and when all sets of said combs have been actuated the entire head of hair will be waved in the desired manner.

It will be understood that prior to the application of the apparatus on the head the hair is moistened with water or with a liquid

that will be effective in causing the hair to retain the waves and after the combs have been actuated as just described the front member 10 of the frame, the chin cup 15 and back neck member 14 are removed from the upper portion of the apparatus and a net or the like is placed over the hair that is held in position by the adjusted combs, and said net and combs are retained on the head until the hair is dry, whereupon the net and combs are removed, leaving the hair in the desired waved condition.

In some instances it may be found desirable to equip the combs or the comb carrying strips with electric connections that include small heating coils, and thus the combs may be mildly heated while applied to the head, and which application of heat will assist materially in the drying of the hair after being waved.

Thus it will be seen that I have provided a hair waving machine that is relatively simple in construction, inexpensive of manufacture, and which may be advantageously employed for imparting to the hair Marcel, water or finger waves.

It will be understood that minor changes in the size, form and construction of the various parts of my improved hair waving machine may be made and substituted for those herein shown and described without departing from the spirit of my invention, the scope of which is set forth in the appended claims.

I claim as my invention.

1. In a hair waving apparatus, a supporting member adapted to be positioned on the head and to extend from the center of the forehead over the head to the nape of the neck, means passing around the neck and around the face for retaining said supporting member on the head, a comb carried by and depending from said supporting member, a pair of combs mounted for operation upon said supporting member and adapted to move parallel with each other and with the comb that depends therefrom, and means for moving the members of said pair of combs simultaneously in opposite directions.

2. In a hair waving apparatus, a supporting member adapted to be applied to the head and to extend from the center of the forehead over the head to the nape of the neck, means passing around the neck and around the face for retaining said supporting member on the head, a comb depending from one edge of said supporting member, a pair of combs carried by and extending lengthwise of said supporting member, said pair of combs lying parallel with each other and with the comb that depends from the the edge of the supporting member, and means for simultaneously moving the members of said pair of combs toward each other.

3. In a hair waving apparatus, a frame adapted to be detachably applied to the head,

a series of curved supporting members detachably connected to said frame, and a pair of movable combs arranged on the underside of each supporting member and projecting downwardly therefrom.

4. In a hair waving apparatus, a frame adapted to be detachably applied to the head, a series of curved supporting members detachably connected to said frame, a pair of movable combs arranged on the underside of each supporting member and projecting downwardly therefrom, and means for simultaneously moving the members of each pair of combs in opposite directions.

5. In a hair waving apparatus, a frame adapted to be removably positioned on the head, a plurality of curved supporting members detachably secured to said frame, a comb, rigidly fixed to and depending from each supporting member, a pair of combs arranged for movement on each supporting member, and means for simultaneously moving the members of each pair of movable combs in opposite directions and toward each other.

6. In a hair waving apparatus, a frame adapted to be positioned on the forehead, neck and chin of the wearer, a series of substantially horse shoe shaped members detachably connected to said frame and adapted to overlie the upper portion of the head, a relatively fixed comb depending from one edge of each horse-shoe shaped member, and a pair of substantially parallel movable combs arranged for operation on the underside of each horse-shoe shaped member.

In testimony whereof I affix my signature.

CHARLES H. McCOY.
